MERCURY ARC RECTIFIER

Filed Dec. 5, 1929

Inventor:
Frank P. Whitaker,
by *Charles E. Tullar*
His Attorney.

UNITED STATES PATENT OFFICE

FRANK P. WHITAKER, OF RUGBY, ENGLAND, ASSIGNOR TO GENERAL ELECTRIC COMPANY, A CORPORATION OF NEW YORK

MERCURY ARC RECTIFIER

Application filed December 5, 1929, Serial No. 411,920, and in Great Britain December 10, 1928.

This invention relates to mercury arc rectifiers, and more particularly to anode lead-in constructions for use in such apparatus.

It is well known that a vacuum tight seal between the anode stem and the anode insulator can be made by a packing of asbestos or similar material, sealed with mercury. With such constructions there is the disadvantage that if the seal leaks the sealing mercury runs down on to the anode itself where its presence may produce back-firing of the rectifier.

The object of this invention is to construct an anode lead-in such that if the mercury leaks from the seal the quantity appearing at any time at the anode surface will not be deleterious.

According to the invention a chamber preferably of annular form is provided immediately below the asbestos packing of the seal. If mercury leaks through the seal it will be able to collect in this chamber, and thus not directly reach the anode surface. The chamber is preferably located so as to be kept cool by the cooling medium provided for the anode stem, and thus such evaporation of the mercury in the chamber as takes place will be slow, and not deleterious.

Further, the chamber for receiving the leakage of mercury may be provided with a drain plug, so that when the anode assembly has been adjusted to be vacuum tight any initial mercury which has leaked in can be drained away. After draining away this mercury the drain plug is replaced.

The accompanying drawing illustrates diagrammatically a typical form of the invention.

In the diagram, 1 is the hollow tubular anode stem, which is closed at its bottom end by a plug 2. The anode stem may be kept cool in any convenient way such as by filling it with water, with suitable means for cooling the water. The anode tip 3 is secured by screwing it into the plug 2. 4 is the annular porcelain insulator through which the current is led into the anode tip through the walls of the vacuum chamber of the rectifier, and by which the anode is insulated from the latter. The insulator 4 is carried by and

sealed vacuum tight to the walls of the vacuum chamber at 5, the details of the construction here not being illustrated as they do not form part of this invention.

The vacuum tight seal between the anode stem 1 and the anode insulator 4 is made by packing the annular space between them with asbestos or some similar material as shown at 6, and covering this with mercury 7, thus providing a vacuum tight seal. Any convenient means, not illustrated, may be used for keeping the asbestos tight, and for retaining the mercury.

Below the seal the insulator is provided internally with a lip 8, bearing on the rim of a member 9 secured to the bottom end of the anode stem. Member 9 is so formed as to provide an annular chamber 10 into which any mercury leaking in from the seal can drip and collect, this chamber being kept cool by the cooling medium inside. The lip 8 of the insulator is pressed against 9 by the washer 11, clamp ring 12, and screws 13.

A drain screw 14 is provided by means of which when the anode tip is removed, any mercury which has collected in the chamber 10 can be drained out.

The anode tip bears against the bottom end of the anode insulator by a flexible gasket 15. Alternatively, a flexible annular metal pressing may be used for 15. Any mercury leaking in from the seal will collect in chamber 10, and as this is cooled, evaporation from it will be slow enough not to be deleterious. Such mercury evaporating out of 10 can escape slowly through the gasket 15, which however fits too tightly for the arc to be able to get to the anode stem or member 9 at the back of the anode tip.

What I claim as new and desire to secure by Letters Patent of the United States, is:

1. An anode lead-in construction for mercury arc rectifiers and the like including an anode stem, an anode insulator, a mercury seal interposed therebetween, and a cooled chamber arranged to collect any sealing mercury that leaks through said seal and to permits its slow evaporation into the interior of the rectifier.

2. An anode lead-in construction accord-

ing to claim 1, in which a drain plug is provided for draining out mercury which leaks in from the seal during its initial period of adjustment.

5 3. An anode lead-in construction according to claim 1 in which a flexible gasket is provided between the skirt of the anode insulator and the anode tip.

10 4. An anode lead-in construction for mercury arc rectifiers and the like including an anode stem, an anode insulator, a mercury seal interposed therebetween, and a cooled chamber closed at the bottom and having an annular wall portion, said chamber being arranged to collect any sealing mercury that 15 leaks through said seal and to permit its slow evaporation over the rim of said wall into the interior of the rectifier.

15 In witness whereof I have hereunto set my hand this 12th day of November, 1929.

20 FRANK P. WHITAKER.
